UNITED STATES PATENT OFFICE.

GEORGE M. FORMBY, OF JACKSONVILLE, FLORIDA.

FIREARM.

1,343,444.

Specification of Letters Patent. Patented June 15, 1920.

Application filed March 23, 1917, Serial No. 156,985. Renewed November 1, 1919. Serial No. 335,104.

To all whom it may concern:

Be it known that I, GEORGE M. FORMBY, a citizen of the United States, residing at Jacksonville, in the county of Duval and State of Florida, have invented certain new and useful Improvements in Firearms; and I do hereby declare the following to be a full, clear, and exact description of the invention, such as will enable others skilled in the art to which it appertains to make and use the same.

This invention relates to certain new and useful improvements in automatic guns and contemplates more especially an improved rifle having an automatic cartridge feeding mechanism.

An object of the present invention is the production of an automatic gun including in combination an automatic cartridge feeding mechanism, and a coöperating breech mechanism and firing chamber for receiving the cartridges in rapid succession and ejecting the empty shells after each cartridge is exploded without the loss of the powers of the gases in the ejection of said shell before the bullet leaves the muzzle of the gun.

Another object of this invention is to produce an automatic gun having an automatic cartridge magazine feeding device designed to successively position loaded magazines beneath coöperating breech and firing mechanism, and means, including the follower of the magazine, for automatically operating the cartridge magazine feeding device, after the last cartridge in each magazine has been delivered to the gun.

A further object of this invention is the production of an automatic gun including in combination a novel form of firing chamber provided in a movable block member and coöperatively associated with the barrel and movable breech block.

A still further object of this invention is to produce an automatic gun having a novel breech mechanism, and a combined multiple magazine cartridge holder and supporting member, both of the said latter elements being detachably secured to the gun in substantially vertical alignment with the aforesaid breech mechanism for effectively balancing the gun when held in the arms, supported upon the knee, or rested upon the ground.

With these and other objects in view the

invention further consists in the combination and arrangement of the several parts hereinafter described and pointed out in the appended claims.

In the drawings which show by way of illustration an embodiment of my invention:

Fig. 1 is a sectional elevation of my improved gun shown supported upon the ground;

Fig. 2 is a top plan view thereof, showing the multiple magazines to one side of the gun, and in a position to be moved beneath the breech mechanism as the cartridges are discharged.

Fig. 3 is an enlarged sectional view through the breech mechanism of the gun showing the position of the firing chamber, and breech-block when the cartridge is to be fired.

Fig. 4 is a horizontal sectional view on the line 4—4 of Fig. 3.

Fig. 5 is an enlarged sectional view similar to that of Fig. 3 showing the position of the firing chamber and coöperating breech-block when the cartridge has been fired and the firing chamber is a short distance in the barrel of the gun.

Fig. 6 is a detail sectional view on the line 6—6 of Fig. 3.

Fig. 7 is a detail cross-sectional view through the coöperating breech-block member.

Fig. 8 is an enlarged sectional view through the breech mechanism showing the position of the firing chamber and the coöperating breech-block when the cartridge is fed into the firing chamber, the prior empty shell having been ejected in the usual manner.

Fig. 9 is an enlarged detail horizontal sectional view through the multiple magazine holder and the spring for actuating the same.

Fig. 10 is a detail vertical sectional view through the magazine holder.

Fig. 11 is a detail horizontal sectional view showing the spring latch means for successively locking the magazine holder as the successive magazines are brought into position, and

Fig. 12 is a detail sectional view through the upper portion of one of the magazines.

The present invention has been designed to facilitate the use of an automatic rifle

- whereby continuous firing may be engaged in. It comprises, among other things, a breech mechanism consisting of a movable firing chamber; a breech block; an automatic cartridge magazine feeding mechanism for successively bringing the loaded magazines beneath the breech mechanism; and means for actuating the aforesaid devices, as will more fully hereinafter appear.
- 10 Referring to the drawings, the gun may be of a standard type and comprises the usual stock 1, barrel 2, and the other usual parts, all of which may be of the ordinary measurements required for army and other uses.
- 15 The improvements contemplated comprise a novel breech-mechanism for successively positioning the cartridges within the firing chamber in a continuous manner for rapid firing. The mechanism for accomplishing this comprises a breech block, a breech chamber 3 which may be formed as a part of the barrel 2, and the former of which is relatively movable as each cartridge is fired and another one positioned in the firing chamber. Cooperating with the movable breech block is a firing chamber 5. The firing chamber 5 is movable within the permanent breech chamber 3 and is withdrawn therefrom after each discharge of a cartridge by the breech block 4. Spring latch mechanism 7 is carried by the breech block 4 and engages the flanged end 8 of the firing chamber, as shown in Figs. 3 and 5. A releasing lug or cam 9 is provided in the path of this latch 7, and as the breech block 4 and firing chamber 5 are moved rearwardly by the recoil from the discharge of the cartridge, the latch 7 will be operated by contacting with the cam or trip 9 and the firing chamber returned to its position in the permanent breech chamber 3. Suitable springs 10 are oppositely disposed within recesses formed in the wall of breech chamber 3, and serve to return the firing chamber 5 (see Fig. 4). These springs 10 are interposed between heads 11 provided on rods 12 secured to the flanged end 8 of the firing chamber. The recoil of the breech block 4 is absorbed by the spring 14 interposed between the end wall of the gun casing and the protruding stud 15 carried by the breech block 4.
- 55 As shown in Fig. 5 of the drawings, the spring 14 is compressed when the breech block 4 has reached its rearward position. A suitable valve 16 is provided adjacent the chamber in which the spring 14 operates and serves to admit air when the cooperating breech block 4 returns to its position carrying with it a cartridge to be positioned in the firing chamber 5.
- 60 The trigger mechanism designed to fire the cartridge when positioned in the firing chamber may be of the usual construction and for the purpose shown herein is con-
- ventionally illustrated as comprising a hammer 17 pivoted at 18 (see Fig. 3). The trigger 19 is pivoted at 20 and as it is pulled by the action of the finger against the tension of the spring 21 the lower end of the hammer 17 is released and pulled by the action of a spring 22, thereby giving a blow to the firing pin 23 for discharging the cartridge. The firing pin 23 may be of usual construction, and is herein shown as returned to its normal position by the spring 24.
- 65 The mechanism for positioning a cartridge as it is fed upwardly from the magazine comprises a lever 25 pivoted at 26 to the cooperating breech block 4 and held against the hammer 17 by a suitable spring 27. It will be seen that as the cooperating breech block 4 moves forwardly the front end of the lever 25 engages the cap end 85 of the cartridge and moves it forwardly into the firing chamber. While the cartridge is being positioned within the firing chamber the movable breech block 4 is momentarily held in the position shown in Figs. 5 and 8 90 by a spring latch device 46 designed to drop into a recess 47 formed in the breech block 4 when it is driven rearwardly by the recoil from the discharge of the cartridge. After the cartridge has been properly positioned 95 within the firing chamber of the block 5, the breech block 4 is released by means of the lever 48 being moved by the flange 8 of the firing chamber 5 as it is retracted and seated against the breech chamber member 3 100 by the springs 10. It will be seen that as the end 49 of the lever 48 is pressed outwardly by the flange 8 of the chamber 5, the opposite end 50 of the lever will release the spring latch 46 and allow the recoil spring 105 14 to force the breech block 4 forward carrying with it a cartridge to be seated against the permanent breech chamber 3.
- 110 The multiple magazine holder comprises the casing 30 into which a plurality of cartridge holding magazines are placed. These magazines are arranged radially with respect to the support for the gun to be presently described. Each magazine comprises guiding walls 31, the upper ends of which 115 are slightly inwardly curved as at 32, and open at their forward ends to facilitate the withdrawal of the cartridge as it is caught by the lever 25 and positioned in the firing chamber. A spring 33 is interposed between 120 the magazine follower 34 and the bottom of the magazine. The purpose of this spring is to feed the cartridges upwardly as they are successively discharged from the gun, the curved portions 32 serving to hold them 125 until the uppermost cartridge is removed.
- 125 The magazine holder is adapted to be moved after each magazine has been exhausted of its contents, and the mechanism for operating the same comprises a spring 130

35 one end of which is secured to the support 36 and the other end of which is secured to the casing 37 secured to the magazine holder. A spring latch 38 is carried by the 6 gun (see Figs. 1, 8 and 11), and serves to lock the magazine holder during the discharge of the cartridges from the magazines as they are successively brought beneath the breech-block mechanism. As the last cartridge 10 in the magazine is fired, the follower 34 is designed to engage the protruding end 39 of the latch 38 and press it inwardly against the action of the spring 40. When the latch 38 is thereby released the spring 35 15 will move the magazine holder in an arcuate direction until the next magazine is reached, when the latch 38, having been freed, will engage the recess 41 formed in said magazine holder and hold the same in position 20 until the contents of that magazine are discharged, after which a similar operation occurs until the entire contents of the magazines carried by the holder are discharged.

The mechanism for ejecting the shell from 25 the firing chamber comprises a spring latch 42 pivoted in the coöperating breech-block member 4. The latch 42 is designed to engage the flange of the shell and hold the same within the recess 43 until the firing 30 chamber 5 has been returned to its position, after which the spring-pressed pin 44 oppositely arranged with relation to the latch 42 tends to kick the shell outwardly through the opening 45 in the gun casing.

35 While I have shown this means for ejecting the shell it will be readily understood that other forms may be employed. The support 36 for the gun is braced at its lower end by the connection 51 extending from the 40 magazine holder. It comprises a rod, the upper end of which is detachably secured to the gun by means of a bolt 52 as shown in Figs. 1 and 2, and the lower end of which is provided with a suitable supporting surface 45 53 preferably of disk like formation. As shown in Fig. 1, the gun is resting upon the ground thereby affording a convenient and stable support for the gun when being discharged from a lying down position. When 50 the gun is fired from a squatting position, the supporting surface 53 is rested upon the knee, thereby giving to the gun a steadiness which is always desirable. When the gun is fired from a standing position it will readily be understood that the loaded magazine 55 holder naturally swings beneath the arm in a substantially balanced position, thereby facilitating the aim and gripping of the gun for accurate shooting.

60 The operation of the gun follows: Referring to Figs. 3, 5 and 8 of the drawings, three positions of the breech mechanism and associated parts are shown. In Fig. 3 the breech mechanism is shown closed in the 65 position for discharging a cartridge. The

chamber 5 is shown firmly seated in the breech chamber 3. The coöperating breech block 4 is shown jammed against the flange 8 of the firing chamber 5, the spring latch 7 thereof having engaged the flange 8 as shown. It will be seen that as the trigger 19 is pulled the firing pin 23 will be struck a blow by the hammer 17 and the cartridge discharged.

As the bullet leaves the shell of the cartridge and has proceeded but a short distance in the barrel of the gun the movable breech block 4 will recoil against the tension of the spring 14 drawing with it the firing chamber 5 by virtue of the spring latch connection hereinbefore described. It will be noted that one end of the firing chamber 5 remains within the breech-chamber 3, thereby confining all of the gases of the explosion until the bullet leaves the muzzle of the gun. As the breech-block 4 reaches its rear-most position the latch 7 is operated by contacting with the lug 9, thereby releasing the firing chamber 5 which is then returned to its seated position within the permanent breech-chamber 3 by the action of the springs 10. Just prior to the firing chamber 5 completely seating in the breech-chamber 3 the flange 8 of the said firing chamber strikes the end 49 of the lever 48 and presses it outwardly, thereby releasing the spring latch device 46 from within the recess 47 and allowing the coöperating breech block 4 to be forced by the action of the recoil spring 14 against the flange 8 of the firing chamber. Before the coöperating breech-block 4 is released, however, a cartridge from the magazine beneath the breech mechanism has been positioned for loading the gun, and it will be seen that as the coöperating breech block 4 is forced forwardly the end of the lever 25 engages the capped end of the positioned cartridge and pushes it from the magazine directing it into the firing chamber 5 just prior to the flange 8 seating against the breech-chamber 3. As the coöperating breech block 4 moves forwardly the cartridge is forced into the firing chamber and the spring latch 42 engages the flange of the shell for holding it within the recess 43. When the cartridge has been discharged and the coöperating or movable breech block 4 recoils, the spring latch 42 serves to hold the empty shell within the recess 43 until the firing chamber 5 has been returned by action of the spring 10, after which the ejecting pin 44 serves to kick the shell outwardly through the opening 45 in the casing of the gun.

When the last cartridge in the magazine 125 immediately beneath the breech mechanism has been discharged, the forward end of the follower 34 is designed to engage the protruding end 39 of the spring latch 38 and press it inwardly against the action of

the spring 40, thereby permitting the controlling spring 35 of the magazine holder to accurately move the said holder until the succeeding magazine is positioned beneath the breech mechanism, at which time the spring latch 38 will engage the recess 41 formed in the upper end of the holder and maintain it in permanent relation to the firing chamber of the gun until the cartridges in that magazine have been discharged, wherupon the operation is repeated until the entire contents of the magazine holder have been exhausted.

When it is desired to detach the magazine holder and support 36 from the gun, the bolt 52 is withdrawn, as will be readily understood. From the foregoing it will be obvious that I have produced an automatic gun capable of effecting a continuous discharge of cartridges and at the same time possessing novel features of action for readily receiving the cartridges in succession.

What I claim is:

1. An automatic gun of the class described including in combination a breech mechanism consisting of a permanent breech-chamber and a movable breech-block, a firing chamber movable in said permanent breech-chamber, means for locking the movable breech-block to the firing chamber for moving the latter from the permanent breech-chamber when the cartridge is exploded, releasing means for said firing chamber, means for returning the firing chamber from its moved position, retaining means for holding the movable breech block in its recoil position, means for releasing the movable breech-block, and a cartridge feeding device for positioning the loaded cartridge in the firing chamber.

2. An automatic gun of the class described including in combination a breech mechanism consisting of a permanent breech-chamber and a movable breech-block, a firing chamber, means including a spring latch for locking the movable breech-block to the firing chamber for moving the latter in the permanent breech-chamber when the cartridge is exploded, releasing means for said firing chamber designed to operate the spring latch when the movable breech-block has reached its recoil position, means including a spring for returning the firing chamber from its recoil position into the permanent breech-chamber, retaining means including a spring latch for holding the movable breech-block in the recoil position, means for ejecting the empty shell as the firing chamber is returned to its normal position in the permanent breech-chamber, means for releasing the movable breech-block, said means being operated by the firing chamber, and a cartridge feeding device for positioning the loaded cartridge in the firing chamber.

3. An automatic gun of the class described including in combination a breech mechanism consisting of a fixed breech-chamber and a movable breech-block, a firing chamber, means including a spring latch for locking the movable breech-block to the firing chamber for moving the latter out of the permanent breech-chamber when the cartridge is exploded, releasing means for said firing chamber designed to operate the spring latch when the movable breech-block has reached its recoil position, means including a spring for returning the firing chamber from its recoil position into the permanent breech-chamber, retaining means including a spring latch for holding the movable breech-block in the recoil position, means carried by the movable breech-block for ejecting the empty shell when the firing chamber is returned to its normal position in the permanent breech-chamber, means for releasing the movable breech-block, said means being operated by the firing chamber immediately before it reaches its normal position in the permanent breech-chamber, and a cartridge positioning device carried by the movable breech-block for directing a loaded cartridge within the firing chamber.

4. An automatic gun of the class described including in combination a breech mechanism consisting of a breech-chamber and a movable breech-block, a firing chamber, means including a spring latch for locking the movable breech-block to the firing chamber for moving the latter from the permanent breech-chamber when the cartridge is exploded, releasing means for said firing chamber designed to operate the spring latch when the movable breech-block has reached its recoil position, means including a spring for returning the firing chamber from its recoil position into the breech-chamber, retaining means including a spring latch for holding the movable breech-block in the recoil position, means carried by the movable breech-block for ejecting the empty shell when the firing chamber is returned to its normal position in the breech-chamber, means for releasing the movable breech-block, said means being operated by the firing chamber immediately before it reaches its normal position in the breech-chamber, and means carried by the movable breech-block for engaging a loaded cartridge and directing it within the firing chamber, and a cartridge magazine feeding device for successively positioning the loaded cartridge within the path of the means carried by the movable breech-block for engaging a loaded cartridge and directing it within the firing chamber.

5. An automatic gun of the class described including in combination a breech mechanism consisting of a breech-chamber and a movable breech-block, a firing chamber mov-

- able in said breech-chamber, means for locking the movable breech block to the firing chamber for moving the latter from the breech-chamber when the cartridge is exploded, releasing means for said firing chamber, means for returning the firing chamber from its recoil position, retaining means for holding the movable breech-block in its recoil position, means for releasing the movable breech-block, a cartridge positioning device carried by the movable breech-block for engaging a loaded cartridge and directing it within the firing chamber, a multiple magazine cartridge holder, and means for automatically positioning a loaded magazine beneath the cartridge positioning device carried by the movable breech-block.
6. An automatic gun of the class described including in combination a breech mechanism consisting of a breech-chamber and a movable breech-block, a firing chamber designed to be moved by the movable breech-block by the recoil from the explosion, means including a spring for absorbing the recoil
- 5 of the movable breech-block, a chamber for said spring, and a valve provided in said chamber for admitting air to the said chamber when the spring returns the movable breech-block to its normal position.
7. A gun of the class described in combination with a cartridge feeding device comprising a multiple magazine cartridge holder, a support for said holder, means including a spring secured to said holder and the said support for successively moving the holder, releasing means for said holder and means for operating the releasing means when the last cartridge in a magazine has been delivered to the gun for permitting the aforesaid spring to move the multiple magazine holder.
- 20 In testimony whereof I affix my signature, in presence of two subscribing witnesses.
- GEORGE M. FORMBY.
